FOREIGN PATENT DOCUMENTS

CA 14560 4/1946

* cited by examiner

Primary Examiner — Elizabeth J Oswecki*(74) Attorney, Agent, or Firm* — Von Rohrscheidt Patents(57) **CLAIM**

The ornamental design for a star, as shown and described.

DESCRIPTION

The sole FIGURE is a front view of a star showing my new design. The broken lines show portions of the star that form no part of the claimed design. All surfaces not shown form no part of the claimed design.

1 Claim, 1 Drawing Sheet
